UNITED STATES PATENT OFFICE.

DANIEL MACKAY, OF PITTSBURG, PENNSYLVANIA.

GLOVE.

No. 852,972.

Specification of Letters Patent.

Patented May 7, 1907.

Application filed September 21, 1906. Serial No. 335,623.

To all whom it may concern:

Be it known that I, DANIEL MACKAY, a citizen of the United States of America, residing at Pittsburg, in the county of Allegheny and State of Pennsylvania, have invented certain new and useful Improvements in Gloves, of which the following is a specification, reference being had therein to the accompanying drawings.

10 This invention relates to certain new and useful improvements in gloves, and the invention has for its object to provide a simple, durable and inexpensive glove particularly designed for bricklayers, hod carriers and similar artisans having rough and heavy articles to handle.

Another object of this invention is to provide a glove having removable tips, whereby said tips can be renewed when worn or injured.

With these and other objects in view which will more readily appear as the invention is better understood, the same consists in the novel construction, combination and arrangement of parts to be hereinafter more fully described, illustrated and specifically pointed out in the appended claims.

Referring to the drawing forming part of this specification, like numerals of reference 30 designate corresponding parts throughout the several views, in which:

Figure 1 is a view of the back of the glove, the wrist clamp thereof being bent to clearly illustrate its construction, Fig. 2 is a view 35 of the front of the glove, Fig. 3 is an end view of the glove, showing the clamp in its natural position, Fig. 4 is a perspective view of a tip.

I construct my improved glove of flexible 40 material as leather, metallic clips and a resilient wrist clamp, these elements being arranged to form a glove adapted to protect the fingers of a hand from rough and injurious surfaces with which the fingers may contact.

45 The flexible material or leather is used to form the back 1 of the glove, the back being substantially rectangular to shield and cover the back of the hand. The back is provided with a thumb piece 2, and with 50 wrist straps 3. Suitably secured to the back of the glove near the rear edge thereof is a resilient wrist clamp 4, which is loosely secured to the wrist straps 3, as at 5. The

wrist clamp 4 is employed to maintain the back of the glove upon a hand.

The forward edge of the back of the glove and the thumb piece 2 are provided with metallic clips 6, said clips being suitably secured to the back and the thumb piece. Each clip is detachably connected to finger and thumb tips 8, which are constructed of leather similar to the back of the glove. Each one of the tips 8 is made of a sufficient length to surround the digits of a hand, and thoroughly protect the same.

65 From the novel construction just described, it will be obvious that I have devised a simple glove, the tips of which can be removed when worn or injured. The leather tips serve to protect the fingers of a hand, 70 while the back of the glove and the wrist clamp thereof simply serve to maintain the tips upon the fingers of a hand.

I do not care to confine myself to the manner of securing the glove upon a hand, or to 75 the size, material or minor details of construction, as such changes as are permissible by the appended claims, may be resorted to without departing from the spirit and scope of the invention.

80 What I claim and desire to secure by Letters Patent, is:—

1. A glove consisting of a flexible back having a thumb piece and wrist straps, a resilient wrist clamp secured to said back, and 85 straps, clips carried by said back and thumb piece, and tips detachably secured to said clips, substantially as described.

2. A glove consisting of a back having a thumb piece, a resilient wrist clamp carried 90 by said back, clips carried by said back and thumb piece, tips, and means to detachably secure said tips to said clips, substantially as described.

3. A glove consisting of a back, clips carried by back, tips detachably secured to said clips, and means carried by said back to hold said glove upon a hand, substantially as described.

95 In testimony whereof I affix my signature 100 in the presence of two witnesses:

DANIEL MACKAY.
